UNITED STATES PATENT OFFICE.

CHARLES H. SEEGMILLER, OF CHICAGO, ILLINOIS, ASSIGNOR OF ONE-HALF TO FRED J. DENNIS, OF CHICAGO, ILLINOIS.

FOLDING BOX.

1,107,852.

Specification of Letters Patent. Patented Aug. 18, 1914.

Application filed May 22, 1911. Serial No. 628,771.

To all whom it may concern:

Be it known that I, CHARLES H. SEEGMILLER, a citizen of the United States, residing at Chicago, in the county of Cook and State of Illinois, have invented certain new and useful Improvements in Folding Boxes, of which the following is a specification, reference being had therein to the accompanying drawing.

10 My invention relates to the construction of paper or paste-board boxes or lids adapted to be supplied to the consumer in knock-down or collapsed form and convertible into box-like form provided with end-flaps having flexible retaining strips adapted to be locked in position between a wall and the associated folded corner-sections when the parts are erected to box-like form, and the object of my invention is to provide a new 20 and improved combination of elements by which the parts may be assembled and shipped in knock-down form and then readily erected in box-like position with the sides and ends retained and held in operative 25 position.

The invention consists in the combinations and arrangements of parts as herein described and then pointed out in the appended claim.

30 My invention is applicable to a box-cover or lid as well as to the box-body itself, and it is understood that the term box in the specification and claim refers to and includes the former as well as the latter.

35 In the accompanying drawings: Figure 1 is a plan view of a collapsed box containing my invention; Fig. 2 is a similar view showing the blank of Fig. 1 with the end-flaps folded inwardly upon the ends; Fig. 40 3 is a sectional view on the line 3—3 of Fig. 2; Fig. 4 is a detail view of one of the end-flaps; Fig. 5 is a similar view of one of the retaining strips; Fig. 6 is an inside view 45 of the box looking toward one of the ends when the parts are erected in box-like form with one end of the flap broken away to better show how the ends of the associated retaining strips are interlocked between the triangular folded end-sections and the end- 50 wall; and Fig. 7 is a sectional view on the line 7—7 of Fig. 6.

The box is formed from a suitable blank A adapted to be folded along the parallel folds or creases a a' to form the box sides 55 B and ends B', the creases or scores form-

ing hinges or flexible joints to erect the sides and ends into box-like form upon the base formed by the main portion or body of the blank; the creases intersect to form the usual rectangular corner-sections C which 60 are scored or creased diagonally as at e so that when the sides and ends are turned up the portions of the corner-sections will form inturned corner-folds lying against the associated end of the box in the usual manner, 65 and to which they may be secured as by staples e' if desired.

On each end B' of the blank is a flap D extending across the end, each flap being flexibly joined or hinged to an end by a 70 suitable crease or score d and folding over when the box is erected to form a retaining flap for the infolded corner-sections C. Each returning flap is provided with a flexible retaining strip E which is secured at 75 its center to the outer face of the flap and along its free edge as by a suitable staple e which preferably also passes through the associated end B' as shown in Fig. 3, though it is of course understood that only the 80 associated parts D and E may be connected by this or equivalent fastening device without in any way departing from my invention or sacrificing any of its advantages. Each flap D is provided near each end with an 85 outwardly facing angular portion or edge d' as for example by forming triangular notches therein, and each strip E near each end is provided with an inwardly facing angular portion or edge e' as for example 90 by forming triangular notches therein, the associated angular edges or portions of these parts facing oppositely and adapted to interlock, and these parts are so arranged that the ends e' of the strip pass to the under 95 or inner side of the flap and extend or project beyond the notches or shoulders of the flaps in position to underlie the infolded corner-sections under which they are passed or tucked when the box is erected. The 100 angular edges or notches in the flap and strip are of such depth that when these parts are in place the outer edges of the strip and flap are flush, and the notches or shoulders of the flaps are located inside the folds of 105 the corner sections when the sides and flaps are turned inwardly to position as clearly shown in Figs. 2 and 6 so that in the process of assembling the parts in collapsed form the placing of the strips on the flaps with 110

their associated angular portions or notches in engagement places the strips in correct alignment and in relation to engage the infolded corner-sections and to receive the 5 fastening staples *e*. The latter are secured at approximately the center of the strips in order to leave the lateral portions of the strips free to flex or bend so that their ends may be easily and readily passed to their 10 final positions between the infolded corner-sections *C* and the associated end *B'* when the parts are erected to box-like form.

When the collapsed box is made the sides and corner-sections are folded over inwardly 15 upon the bottom; if the box-ends *B'* and the end-flaps *D* are secured together as for example by the staples *e* the end-flaps are in-turned as shown in Fig. 2 and the staples *c'* need not be employed. If the end-flaps and 20 box-ends are not secured together as by the staples *e* the end-flaps are extended as shown in Fig. 1 and the staples *c'* or equivalent fastenings are employed to secure one portion of each corner-section *C* to the associated end *B'*.

Where the collapsed box is erected to box-like form the sides and ends are erected in the usual manner, the corner-sections *C* folding inwardly along their diagonal lines *c* to 30 lie against the inner faces of their associated ends *B'*, and the free ends *e²* of the retaining strips *E* are then tucked or passed under the infolded corner-sections to position between these sections and the inner faces of the ends 35 where they are held in place by the interlocking of their angular edges or notches with the corresponding opposite angular edges or notches of the flaps. These angular portions or notches thus co-operate to properly position the retaining strips upon the 40 end-flaps. The ends of the strips in place between the infolded corner-sections and ends hold the flaps *D* in position to retain the corner-sections in their infolded position 45 to keep the sides and ends erected. The fact that the strip is placed on the outer or upper face of its associated flap and along the edge thereof prevents the strip from bending or flexing when the parts are set up with its 50 ends inserted between the infolded corner

sections and the associated end-wall and enables it to hold the lateral or end-portions of its associated flap against rising from their associated wall when the blank is set-up or erected; this prevents the corner-sections from unfolding and retains the sides and ends in their erect positions. The fastening of the retaining strips at their centers leaves their lateral portions free to be 55 easily flexed or bent to pass under the infolded corner-sections.

It is of course obvious that the retaining strips and flaps will interlock even if the latter are cut away at their ends and the former at its center as along the lines *d²* 60 and *e³* respectively, as the opposing faces or edges co-act in any event; also the retaining strips may be straight or with plain edges. Various other changes or modifications may be made within the scope of the appended 70 claim without departing from the present invention.

I claim:—

A collapsed box, comprising a base, a pair of side walls and a pair of end walls flexibly 75 connected to the base, one set of walls lying flat on the base with folding corner-sections at their ends, flaps flexibly secured to the other set of walls and having their edges notched near their ends inside the folds of 80 the corner sections, and a flexible retaining strip secured near its center to the upper face of each flap along the edge thereof and having notches near its ends engaging the notches of the associated flap, the notches being of such depth that the edges of the associated strips and flaps are flush, said strips 85 being of sufficient length that their ends project beyond the notches and lie between the infolded corner-sections and the associated end-wall and hold the ends of the flaps against rising from their associated end-wall when the parts are erected in box-like form.

In testimony whereof I affix my signature in presence of two witnesses.

CHARLES H. SEEGMILLER.
